(57) **CLAIM**

I claim the ornamental design for triple head LED solar motion light with vertical LED section, as shown and described.

DESCRIPTION

FIG. 1 is a perspective view of the first embodiment of my ornamental design of the triple head LED solar motion light with vertical LED section;

FIG. 2 is a right side elevation view of the triple head LED solar motion light with vertical LED section of FIG. 1;

FIG. 3 is a front elevation view of the triple head LED solar motion light with vertical LED section of FIG. 1;

FIG. 4 is a left side elevation view of the triple head LED solar motion light with vertical LED section of FIG. 1;

FIG. 5 is a rear elevation view of the triple head LED solar motion light with vertical LED section of FIG. 1;

FIG. 6 is a top plan view of the triple head LED solar motion light with vertical LED section of FIG. 1;

FIG. 7 is a bottom plan view of the triple head LED solar motion light with vertical LED section of FIG. 1;

FIG. 8 is a perspective view of the second embodiment of my ornamental design of the triple head LED solar motion light with vertical LED section;

FIG. 9 is a right side elevation view of the triple head LED solar motion light with vertical LED section of FIG. 8;

FIG. 10 is a front elevation view of the triple head LED solar motion light with vertical LED section of FIG. 8;

FIG. 11 is a left side elevation view of the triple head LED solar motion light with vertical LED section of FIG. 8;

FIG. 12 is a rear elevation view of the triple head LED solar motion light with vertical LED section of FIG. 8;

FIG. 13 is a top plan view of the triple head LED solar motion light with vertical LED section of FIG. 8; and,

FIG. 14 is a bottom plan view of the triple head LED solar motion light with vertical LED section of FIG. 8.

The portions shown in broken lines are for illustrative purposes only and form no part of the design.

1 Claim, 8 Drawing Sheets
